UNITED STATES PATENT OFFICE.

LOUIS BELL AND FRANCIS H. ROOT, OF CHICAGO, ILLINOIS.

TEMPERATURE-REGULATOR.

SPECIFICATION forming part of Letters Patent No. 470,653, dated March 15, 1892.

Application filed January 14, 1890. Serial No. 336,945. (No model.)

To all whom it may concern:

Be it known that we, LOUIS BELL and FRANCIS H. ROOT, both citizens of the United States, residing at Chicago, in the county of Cook and State of Illinois, have invented a certain new and useful Improvement in Temperature-Regulators, of which the following is a specification.

Our invention relates to a system of temperature-regulation, and is designed to provide simple, economical, and highly-efficient means for automatically controlling the service of various heating agents—such as hot water, steam, and gas—it being here observed that while highly serviceable and effective as a means for controlling the flow of steam or hot water to radiators, it is also particularly serviceable as a means for regulating the flow of natural gas to such stoves or heaters as may be supplied with such fuel. As a further incident, however, to our invention the opening and closing of a stove or furnace damper can be readily attained.

In carrying out our invention we provide a thermostat involving a hermetically-sealed chamber containing a volatile liquid and a movable abutment subject to pressure due to vapor-tension within such chamber. By such arrangement we provide at a comparatively small cost a highly sensitive and efficient thermostat. The movable abutment serves to operate a valve, which can be employed for several purposes. Thus the valve can be employed for opening and closing a passage through which gaseous fuel is supplied to a stove or heater, or it can be employed for controlling the supply of gaseous fuel to one or more burners arranged in conjunction with a device or regulator similar to the thermostat, but operated by the heat from a flame or flames and employed for controlling either a damper or the flow of steam or hot water, an advantage of this last-mentioned arrangement being that the thermostat and the regulator can be arranged at any desired distance apart, and, if so desired, be arranged in different apartments. The thermostat itself may, however, directly control the flow of steam or hot water, as well as gas, as will hereinafter be apparent.

In the accompanying drawings, Figure 1

represents in section an apparatus embodying the thermostat and regulator, with the valve of the thermostat open and the valve of the regulator closed. Fig. 2 is a similar view with the valve of the thermostat closed and the valve of the regulator open. Fig. 3 illustrates, mainly in section, the thermostat and regulator with a damper subject to the latter. Fig. 4 is a central section through the thermostat, and represents it as being particularly adapted for directly controlling the flow of gas in a main service pipe or passage. Figs. 5 and 6 are like views with the valve in different positions. Fig. 7 is a section on line 7-7 in Fig. 5.

In said drawings, A, Figs. 1 and 2, indicates a portion of a valved passage, which can be used for the delivery of gas, steam, or water from a suitable source of supply to the heater or radiator or other apparatus to be supplied. The valve B for opening and closing this passage is subject to and operated by the action of a movable abutment C, which is in turn subject to and operated by fluid-pressure within a closed chamber. As one of various ways in which this movable abutment can be constructed and arranged it may be and, as herein shown, is formed by a flexible diaphragm C, arranged within a shell or casing D and secured thereto along its edge portion. The valve B is connected with said diaphragm or movable abutment, which latter divides the space within the casing, so as to provide at one side of the diaphragm a closed chamber d and leave at the opposite side of the diaphragm suitable working space, as at d'. By such arrangement the diaphragm forms one of the sides of the hermetically-sealed pressure-chamber d. When the movable abutment which is thus formed by the flexible diaphragm is in its normal position, as in Fig. 2, the valve B will be open, it being understood that the passage A can of course be provided with any suitable hand-operated cock. The movable abutment can be normally maintained in such position in any suitable way—as, for example, the diaphragm may have sufficient inherent elasticity to cause it to normally assume a position which will open the valve on its seat, or the diaphragm can be subject to a spring. The pressure-chamber

d can be entirely filled with a fluid, which when subject to a sufficient increment of heat will expand, so as to move the abutment *C* in a direction to cause the valve to close. In 5 place, however, of thus entirely filling the pressure-chamber with a body of fluid we may and prefer to place within such chamber a small quantity of some volatile fluid—such as ether, chloroform, or other fluid—which will 10 readily vaporize, in which way the pressure for operating the movable abutment will be due to the vapor tension within the pressure-chamber, while the vapor tension will be dependent upon the degree of heat to which the 15 wall or walls of the pressure-chamber is or are exposed.

In order that the degree of vapor-tension within the pressure-chamber may be controlled by external temperature, we provide 20 a burner *E* for a pilot-flame, which is subject to and controlled by a thermostat *F*, under an arrangement, whereby when, for example, a desired temperature exists within such room or hall as the thermostat *F* may be arranged, 25 the supply of gas for feeding the pilot-flame will be so small that the flame will be reduced to a minimum and be incapable of affording sufficient heat to raise the vapor-tension within the pressure-chamber *d* to an extent to 30 cause the valve *B* to close, while on the other hand should said external temperature rise to an undesirable degree, the thermostat *F* will be so operated as to let onto the pilot-flame burner a supply of gas sufficient to 35 cause a flame which will at once so heat the contents of pressure-chamber *d* as to increase the vapor-tension therein and thereby operate the movable abutment and close either partially or entirely its allotted valve *B*. This operation 40 cuts off or regulates the flow of steam, water, or gas through the supply-passage *A*, and hence permits the radiator or heater supplied therefrom to cool down.

With reference to further matters of construction the burner for the pilot-flame is arranged to enter a chamber *G*, which may have 45 its walls suitably perforated, so as to supply air to the flame. The wall *d*² of pressure-chamber *d* is exposed within the pilot-flame chamber *G*, so that it may be subject to heat from the pilot-flame.

The thermostat *F* comprises a suitable case *f*, which contains a hermetically-sealed pressure-chamber *f'*, having two opposing walls, 55 one of which is formed by a movable abutment *H*, (preferably consisting of a flexible diaphragm,) while the opposite wall *f*² is desirably formed by a thin metal plate that is corrugated in order to provide an increased 60 exposure of surface to the external air. The pressure-chamber *f'* contains a small quantity of some highly-volatile fluid, such as hereinbefore described, in connection with the pressure-chamber *d*, it being observed that 65 while the pressure due either to the expansion of a body of fluid or to vapor-tension within pressure-chamber *d* results from the

heating capacity of the pilot-flame, the corresponding pressure within pressure-chamber *f'* is due to the heat of the surrounding air. 70

As an illustration of the way in which the feed of gas to the pilot-flame can be controlled by the movable abutment *H*, the chamber *f'* at one side of said movable abutment connects with a supply-pipe *I*, through the medium of a valved port *K*, and connects with the delivery-pipe *L* through the medium of an open passage *l*. The valve *k* for opening and closing port *K* is connected with and operated by the movable abutment *H*, and is 80 normally closed, as in Fig. 2—that is to say, at a proper or desirable temperature, the position of the movable abutment *H* will be such as to hold the valve *k* closed. When, however, the vapor-tension within chamber *f'* is 85 such as to subject the movable abutment *H* to what may be regarded as more than normal pressure, the valve will be opened, as in Fig. 1, so as to allow a supply of gas to flow to the pilot-flame burner. When the valve 90 of the thermostat is closed, it is desirable that there should still be a supply to the pilot-flame burner sufficient to maintain a small flame, which will be in readiness for augmentation as soon as the thermostat-valve has 95 opened. To such end we provide the chamber *f*⁴, which is intermediate of pipe *I* and chamber *f'*, and which forms part of a general passage-way, with a by-passage consisting of a small port or orifice *f*⁵, through which, when so desired, gas may escape into the passage at the delivery side of valve *k*—as, for example, into the portion *l* of the general passage-way. This port *f*⁵ can be opened or closed or varied in area by any suitable 105 valve—as, for example, by a set-screw *M*, having one end adapted to form a valve.

The thermostat can be adjusted so that it will respond to any determinate increase of temperature. This adjustment can be attained in various ways, the principle involved being to render the movable abutment more or less responsive. As an illustration of a way in which this desired result can be attained, we have pivoted within chamber *f'* a 110 lever *N* and arranged between one end of said lever and the movable abutment *H* a spring *P*. The other end of this lever is engaged by an adjusting-screw *Q*, which can be adjusted so as to vary the degree of compression of the spring between the lever and the movable abutment. By such arrangement the lever can be positioned so that the degree of spring-resistance in opposition to the movement of the movable abutment in a direction to open 115 the valve can be determined with great nicety, and hence the thermostat can be set to respond only to such degree of heat as may suit the occupant of the room or other person interested in its temperature. 125

In Fig. 3 the pilot-flame is controlled by a thermostat *F*, similar to that hereinbefore described. In this figure, however, the movable abutment *C* corresponds with the mov-

able abutment C in preceding figures and serves to operate a damper, it being understood that the bar R may form a portion of any suitable valve or damper device and that it can be connected with the movable abutment in any suitable way—as, for example, by an arm r, pivoted to the bar and having an enlarged end in contact with the movable abutment. Obviously various forms of dampers can be used, and hence we do not limit ourselves to any particular construction.

As hereinbefore stated, the valve of the thermostat is normally closed, while the valve which serves to open and close the supply-passage leading to a radiator or heater is normally open. It is understood, however, that in practice such supply-passage either at the radiator or heater or at any desired point will as a matter of course be provided with a suitable cock which can be opened and closed by hand.

In Figs. 4, 5, 6, and 7 we have shown the thermostat more particularly adapted to serve as a means for directly establishing and cutting off the flow of gas from a suitable source of supply to a stove or heater.

This apparatus is particularly adapted for controlling the flow of natural gas, although of course it can be employed for controlling the flow of steam or water or any gaseous fuel. In said figures the movable abutment H can be subject to vapor-tension within the pressure-chamber f', as in preceding figures. The valve U is connected with the movable abutment and is normally open, so that gas may flow from the supply portion S of the passage-way to the delivery portion S' thereof, or from the latter to the former, according to which portion is intended to be at the delivery side of the valve. A by-passage consisting of a small aperture can be provided to permit such leakage as will prevent the flame in the stove or heater from being entirely extinguished when the valve U is closed upon its seat T, and a small valve W can be provided for closing and opening said aperture. In said figures we have also shown a spring and lever similar to the spring and lever in preceding figures. While, therefore, the thermostat

illustrated in the last four figures corresponds generally with the thermostat of the preceding figures, it will be noted that, in place of employing it to control the supply of gas to a pilot-flame, we employ it to control the flow of gas through a main service pipe or passage, of which S and S' represent two portions.

In Fig. 3 the lever N' is a spring-lever, and hence the spring P (shown in preceding figures) is dispensed with.

Claims for certain details in the construction of the thermostat herein shown are now made by us in our application, Serial No. 368,426, filed October 17, 1890, as a division of this application.

What we claim as our invention is—

1. In a system of temperature-regulation, a closed fluid-chamber containing a suitable fluid, a movable abutment subject to pressure within said chamber, and suitable means for applying the heat of a pilot-flame to heat the fluid within said chamber, so as to create pressure therein.

2. The combination, substantially as hereinbefore set forth, of a closed fluid-chamber containing a suitable fluid, a movable abutment subject to pressure within said chamber, means for applying the heat of a pilot-flame as an agent for heating the fluid, a suitable source of supply for feeding the pilot-flame, and a thermostat for automatically controlling the supply to said pilot-flame.

3. The combination, substantially as hereinbefore set forth, of a closed chamber containing a suitable fluid, a movable abutment subject to pressure within said chamber, a valved passage having its valve controlled by the movable abutments, means for applying the heat of a pilot-flame as an agent for heating the fluid within said chamber, a suitable source of supply for feeding the pilot-flame, and a thermostat for automatically controlling such supply.
